UNITED STATES PATENT OFFICE

OSCAR L. COFFEY, OF HARVEY, ILLINOIS, ASSIGNOR TO WHITING CORPORATION, OF HARVEY, ILLINOIS, A CORPORATION OF ILLINOIS

GEAR CASE

Application filed September 22, 1928. Serial No. 307,657.

The invention relates to gear cases.

In cases for gearing, such, for example, as the cases used in trolleys on cranes, it has been found desirable to fabricate the structure, so far as possible, of wrought or plate metal, and one object of the invention is to provide an improved gear case which is fabricated of plate metal and in which the gearing is carried or journalled in a supplemental cast frame which can be readily machined before it is inserted into the case, and so that the shell forming the case will not require any machining.

Another object of the invention is to provide an improved gear-case structure in which the shell is fabricated of plate metal and is provided with a cast frame in which the gearing is mounted or journalled.

Other objects of the invention will be apparent from a consideration of the following detailed description.

The invention consists in the several novel features hereinafter set forth and more particularly defined by claims at the conclusion hereof.

In the drawings which accompany and form a part of this specification or disclosure and in which like numerals of reference denote corresponding parts throughout the several views: Fig. 1 is a side elevation of a crane trolley or truck embodying the invention. Fig. 2 is a plan, the cover of the gear case being removed. Fig. 3 is a section taken on the line 3—3 of Fig. 1. Fig. 4 is a perspective of the lower section of the gear-case. Fig. 5 is a perspective of the supporting frame for the gearing separated from the case. Fig. 6 is a section taken on the line 6—6 of Fig. 1. Fig. 7 is a section taken on the line 7—7 of Fig. 1.

The gear case which forms the subject matter of the invention is exemplified in connection with the truck frame of a trolley for a crane. The truck frame is composed of a base 6, underlying cross-beams 5, and brace and tie bars 7. Bearing brackets 8 are secured to the frame, and wheels 9 have their axles journalled in said brackets. The base 6 is composed of a plate 6^a at the side thereof, over which the gearing for driving the hoist-

ing drum is mounted, and which forms the bottom of the case for said gearing, and a central transverse plate 6^b. A mounting plate 12 for a motor 13 for propelling the truck overlaps and is secured to portions of plates 6^a and 6^b. These plates are welded to the beams 5 to form a rigid structure. A motor for operating a hoisting drum 15 through suitable gearing, is mounted on plate 6^b. The gearing for driving the hoisting drum comprises a shaft 16 which is driven by the motor through a shaft section 16^a and flexible coupling 16^b; a pinion 17 fixed to shaft 16; a gear 18 meshing with pinion 17; a shaft 19 driven by the gear 18 through a suitable load brake which may be of the construction set forth in an application filed by me September 20, 1928, Serial No. 307,372; a pinion 20 fixed to shaft 19; and a gear 21 meshing with pinion 20 and fixed to the hoisting drum 15 and rotating with the shaft 22 for said drum.

In practice it is necessary to provide an enclosing case for this gearing, which is adapted to contain oil for lubricating the gearing and preventing excessive heating of the load brake. According to the present invention this gear case is composed of plates which are welded together so lubricant will be retained therein. The plate 6^a of the truck base forms the bottom of the gear case. Vertical end plates 23 and 24, and side plates 25 and 26 are welded together to form the lower section of the gear case. These plates extend upwardly approximately to the axis of shafts 16, 19 and 22. The top of the case is formed by a cover section 30 which is also built up of plates welded together. An angular bar 31 is secured to the lower margin of section 30 and has a horizontal flange 31^a adapted to rest on the upper edges of the plates forming the lower section of the case and a vertical flange 31^b to lap the outer faces of said plates to form a substantially tight joint between the case-sections. U-shaped handles 32 are secured to the cover. A recess or pocket for one of the truck-wheels 8 is formed in the lower portion of the lower section of the case by vertical plates 33 and 33^a and a horizontal plate 33^b. The meeting edges of all of the plates forming the

lower section of the box are welded together, as at 34, and the vertical plates are welded to the base plate 6^a at 35 to form a rigid rectangular structure. A case frame 36 is mounted in the lower section of the case, and is adapted to support the gearing for operating the drum 15. This frame comprises sides 36^a and 36^b, ends 36^c and 36^d, and a cross-bar 36¹, all of which are integrally formed or cast together. A spacing and reinforcing plate 38 is welded to the inner face of the plate 26, and spacer and reinforcing plates 39 and 40 are welded to the inner face of plate 25. Bolts 37 extend through the frame-sides and box-sides and the spacing plates to removably secure the frame 36 in the lower section of the case. This frame is provided with a pair of aligned seats 36^f to receive the bearings for the shaft 16 which are held in the seats by caps 41; a pair of aligned seats 36^g to receive or form bearings for the shaft 19, and a seat 36^h to receive or form a bearing for the shaft 22 of the hoisting drum. Caps 42 are adapted to secure the shaft 19 in the frame. Plate 26 is formed with a semi-circular opening 26^a, through which the hoisting drum 15 extends. Side 36^b of frame 36 is formed with an opening 36ⁱ for the drum. A semi-circular groove 36^k is formed in the outer face of side 36 of the frame to receive and retain a packing ring 44 around the drum, for the purpose of preventing the escape of lubricant.

The frame is machined before it is inserted into the case, and it is cast with an integral cross-bar 36^e to rigidly cross-connect the sides of the frame and prevent breakage while the frame is being machined. After the frame has been machined and before it is inserted in the case, the bar 36 is cut away.

The invention exemplifies a case for gearing which is formed of plates of metal welded together and an inserted frame which carries the gearing-bearings and can be machined before it is inserted in the case. The frame forms a unit which can be removed from the case conjointly with the gearing, or which permits any of the shafts to be separately removed. The plate-metal formation of the case renders it strong and durable, and makes it possible to form it as an integral part of the base of the truck or other supporting structure.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. The combination of a case comprising a lower section formed of a bottom plate, side and end-plates of wrought metal welded together and a removable cover section formed

of a top plate, side and end plates of wrought metal welded together, the side and end plates of the cover section being adapted to fit against the side and end plates of the lower section respectively, a cast metal frame disposed in and secured to the lower section, and gearing mounted in the frame and enclosed by the two sections. 70

2. The combination of a case comprising a lower section formed of a bottom plate, side and end plates of wrought metal welded together and a removable cover section, a cast metal frame disposed and secured to the lower section of the case, plates welded to the inner faces of the side plates and arranged to space the frame from said side plates, and gearing mounted in the frame. 75

3. The combination of a case comprising a lower section formed of wrought metal plates welded together and a removable cover-section, a rectangular, cast metal frame disposed in the lower section of the case and embodying sides and ends, spacer-plates for the frame welded to certain plates of the lower section and positioned so as to engage the sides 85 of the frame, bolts extending through the spacer-plates and the frame-sides for securing the frame in said lower section of the case, and gearing mounted in the frame.

4. The combination of a case comprising a bottom plate, end plates and side plates of wrought metal all welded together, a cast metal frame disposed in the case, spacer-plates welded to the side-plates, bolts extending through the side and spacer plates for securing the frame in the case, and gearing mounted in the frame. 95

5. The combination of an enclosing case comprising a bottom-plate, side and end plates of wrought metal welded together so as to form a fluid tight compartment for retaining a lubricant, a cast metal frame in the compartment connected to the case so that it is supported thereby and having bearings machined therein, and gearing mounted in the frame so that it is lubricated by the lubricant and embodying shafts journaled in the aforesaid bearings and extending through openings in the side plates of the case. 105

6. The combination of an enclosing case comprising a bottom-plate, side and end plates of wrought metal welded together so as to form a fluid tight compartment for retaining a lubricant, a cast metal frame disposed in the compartment and secured to the side plates of the case so that it is held in spaced relation with respect to the bottom-plate, and gearing mounted in the frame. 115

7. The combination of an enclosing case comprising a lower section formed of wrought metal plates rigidly secured together, and a removable cover section formed of wrought metal plates rigidly secured together, a cast metal frame disposed in and supported by the lower section of the case, and 125

130

gearing including a shaft and mounted in the frame, the lower section and cover section having complementary openings formed in two of the plates thereof through which the
5 shaft extends.

8. The combination with a truck embodying a base plate, of an enclosing case comprising side and end plates of wrought metal rigidly secured together, said plates being secured to the base plate of the truck and forming therewith a compartment, a cast metal frame disposed in the compartment and supported by the case, and gearing mounted in the frame.
10
15 9. The combination with a wheeled truck embodying a base plate, of an enclosing case mounted on the base plate and formed of wrought metal plates arranged to form a pocket for one of the wheels of the truck and a fluid tight compartment, a cast metal frame disposed in the compartment and supported by the case, and gearing mounted in the frame.
